UNITED STATES PATENT OFFICE

EDGAR B. SYMONS, OF HOLLYWOOD, CALIFORNIA, ASSIGNOR TO NORDBERG MANUFACTURING COMPANY, OF MILWAUKEE, WISCONSIN, A CORPORATION OF WISCONSIN

JAW CRUSHER

Application filed July 24, 1930. Serial No. 470,277.

My invention relates to an improvement in crushers, and particularly to an improvement in jaw crushers. A particular embodiment of my invention is a jaw crusher having one normally fixed jaw, and a normally moving jaw together with means for moving the moving jaw toward and away from the normally fixed jaw. One object of my invention herein described, is to provide improved lubricating means for a crusher of the type described. Another object is the provision of improved driving means or actuating means for the moving jaw of a jaw crusher. Another object is the provision of improved means for protecting the bearings of the jaw crusher and for preventing the access of dirt and grit thereto. Other objects will appear from time to time in the course of the specification and claims.

20 I illustrate my invention more or less diagrammatically in the accompanying drawings, wherein—

Figure 1 is an end elevation;

Figure 2 is a section on the line 2—2 of Figure 1;

Figure 3 is a side elevation;

Figure 4 is a section on the line 4—4 of Figure 2; and

Figure 5 is a section on the line 5—5 of Figure 2.

Like parts are indicated by like symbols throughout the specification and drawings.

Referring to the drawings A generally indicates any suitable base or foundation or surface upon which the crushing machine may be mounted. The crushing machine frame generally indicated as A¹ includes any suitable bottom plate or flange portions A² which may be bolted, as by the bolts A³, to the foundations A. Preferably formed integrally with the plates or flanges A² are the upwardly extending frame members A⁴ between which is formed the tank portion having the bottom wall A⁵, the side walls A⁶ A⁷, the top wall A⁸ and the transverse baffle or partition A⁹, depending from the top A⁸.

In the upper portion of each of the members A⁴ is a bearing or shaft engaging portion B to which may be locked the opposed shaft engaging portion B¹ as by the bolts

B² and nuts B³. The shaft B⁴ is thereby mounted on and locked in relation to the frame members A⁴, extending transversely and horizontally between them. Surrounding said shaft B⁴ is a bearing bushing B⁵ of any suitable anti-frictional or wear taking material.

Surrounding the shaft B⁴, and adapted to rotate thereabout, is the hub C from which extends the jaw structure proper C¹. Preferably the bushing B⁵ is keyed to rotate with the hub C, about the outer surface of the shaft B⁴. As strengthening and reinforcement for the plate C¹ are provided a plurality of ribs C² which extend, as shown in Figures 1 and 2, from the hub C downwardly along and beneath the plate C¹, the rib C² having in it an enlargement in the form of a perforated boss C⁵. The ribs C² terminate at their lower or outer ends in a transverse rib C⁶. A corresponding rib C⁷ extends across the bottom of the plate C¹, the ribs C⁶ and C⁷ being connected by longitudinal ribs C⁸, to form in effect a box structure, the purpose of which will later appear. C¹⁰ are a plurality of lugs projecting from the bottom of the plate C¹ which are provided with apertures C⁹.

In order to actuate the jaw a driven shaft D is provided with an eccentric portion D¹. The shaft may be actuated as by the pulley or pulleys D², but it will be understood that any suitable drive may be employed. The shaft D may rotate for example in bearings D³ D⁴ formed in or associated with the opposite frame member A⁴. D⁵ indicates any suitable bearing bushings. Surrounding the eccentric portion D¹ of the shaft is a split sleeve formed with the boss D⁶ and D⁷ which may be locked together as by the bolts D⁸ and nuts D⁹. Within the sleeve so formed, and surrounding the eccentric portion D¹ is any suitable bearing bushing or bushings D¹⁰, indicated in Figure 2 as split. Upwardly projecting from the member D⁶ is an arm D¹¹ having inset in its outer surface a bearing block D¹¹. A corresponding bearing block D¹² is inset in the bottom of the jaw plate C¹, and a roller rod or bearing rod D¹³ is interposed between them, the blocks

being channeled to receive it and conform to its cylindrical exterior. It will be understood that as the shaft D rotates the eccentric portion D¹ will impart to the arm D¹⁰ and thus to the jaw plate C¹ an oscillating or reciprocating movement. In order to maintain constant contact with the roller D¹³ with the opposed blocks D¹¹ D¹², thus maintaining a firm and constant driving connection I provide the following.

Extending through the apertures C⁹ of the lugs C¹⁰ is a tube E the ends of which pass through eye-bolts E¹. The eye E² of each such bolt is held upon the end of the tube E, as by a washer I³ which may be fashioned in any suitable manner upon the tube E. I may for example employ a cotter pin I⁴. It will be understood that the ends of the tube E pass outwardly through the casting and that the eye-bolts E¹ are exterior to the members A⁴ of the casting. This aperture is indicated for example at I⁵ in Figure 3, the aperture being of sufficient size to permit a substantial movement of the tube E in relation to the frame. The aperture also permits inspection of interior parts. Each eye-bolt E¹ passes through a lug I⁶ formed on the exterior of the frame member A⁴ and apertured as at I⁷ to permit the bolt to pass therethrough. An abutment I⁸, below said lug, is mounted upon each eye-bolt E¹, in the form of a stout washer which may be positioned as by the nuts I⁹ upon the screwthreaded end portion I¹⁰ of the eye-bolt. Compressed between the abutment or washer I⁸ and the lug I⁶ is indicated a spring I¹¹. It will be understood that the spring tends to draw the plate C¹ downwardly toward the shaft D, and thereby maintains a constant working and bearing connection between the roller D¹³ and the opposed blocks D¹¹ and D¹².

As a bearing or wear taking member to effect the actual crushing I may employ for example the face or crushing plate G. Its opposed edges and bevelled as at G¹ G². The lower bevelled edge G¹ is gripped by the overhanging portion G³ of the lower edge of the plate C¹. The upper edge is clamped, as by the wedge block G⁴. As shown in Figure 2 the plate C¹ is provided with a bevel, outwardly inclined surface G⁵ and, as will be seen from Figure 2, the wedge block G⁴ performs the double function of drawing down the upper edge of the plate G, and of thrusting the plate G longitudinally against the overhang G³ at the bottom of the plate C¹. The wedge blocks G⁴ may be drawn down as by the bolts G⁶, with their nuts G⁷, the bolts passing through the bosses C⁵. G⁸ indicates a wear taking plate adapted to protect the hub C from battering. It is removably mounted, as by the bolts G⁹ with the nuts G¹⁰. G¹¹ is a batter plate secured as at G¹² to the lower edge of the plate C¹ below the lower edge of the wear plate G.

The jaw plate C¹ is also provided with side flanges G¹³, upwardly projecting, and generally aligned with the downwardly projecting flanges C⁸. The flanges G¹³ support and align the side plates G¹⁴. The plates G¹⁴ have the additional function of guiding the material passing between the crushing jaws, and preventing lateral escape from the crushing space. These plates G¹⁴, which are removable and renewable, move unitarily with the lower jaw structure.

It will be understood that, opposed to the movable lower jaw below described, is an upper jaw which is normally fixed. I provide means, however, for permitting movement of the upper jaw in case uncrushable material, such as tramp iron, passes through the crushing cavity. Referring for example to Figure 3, it will be seen that the side frame members A⁴ are provided at their upper edges with laterally expanded portions K in the form of flanges laterally outwardly extending from the main web or plate A⁴. These flanges are provided with an outer downwardly turned portion K¹. The ends are supported for example by the inclined edged webs K², formed preferably integrally with the plate A⁴. An intermediate web or support K¹⁵ may also be employed. At two points, preferably adjacent the opposite edges of the portion K, it is recessed as at K³ to receive cylindrical projections K⁴ from the jaw plate supporting elements generally indicated as L. The members K⁴ are normally held seated in the position in which they are shown by the securing or abutment plates K⁸ which overlie them and which are apertured or formed as at K¹⁶ to conform to them. These members K⁸ are downwardly thrust against the members K⁴ and the abutment webs or flanges K, for example by the employment of a plurality of bolts K⁹. These bolts extend through the members K⁸ and the flange K, out of line with the members K⁴. Abutments members K¹⁰ are provided and between the members K¹⁰ and the lower surface of the flange K are compressed a plurality of springs K¹¹. K¹² indicates lock nuts for the tops of the bolts K⁹ and K¹³ indicates nuts or washers for the bottoms. It will thus be seen that the springs K¹¹ normally draw the members K⁸ downwardly toward the flanges K, whereby the jaw structure below described is normally held fixed in relation to the frame members A⁴. Secured to the jaw plate supporting elements L as by the bolts L¹ is a carrier M for the lower fixed jaw plate M¹ which may be secured to the carrier M by any suitable means.

In order to maintain proper lubrication of the moving parts and to prevent the access of dust to moving parts I provide the following system. Projecting upwardly about the connection D¹⁰ between the eccentric D¹ and the lower jaw structure C¹ I provide a surrounding housing structure generally indi-

cated as O. This housing O is bolted as at O¹ to the oil container which includes the walls A⁵, A⁶, A⁷, A⁸ and projects upwardly about the member D¹⁰. It terminates in two concentric and somewhat arcuate walls O² O³ opposed to washers or wiping members O⁴ O⁵ on the flanges C⁶ and C⁷ respectively of the plate support or jaw C¹. It will be understood that the form of the opposed parts is such that as the jaw oscillates about its center of rotation the wiping members contact the exterior of the walls or members O² O³, preventing any access of dust to the closed housing thus formed. O⁶ indicates a baffle adapted further to direct what slight dust does penetrate the housing away from the bearing roller D¹³. It will be understood that the packing or wiping means O⁴ O⁵ are continued as at O⁷ along the flanges or walls C⁸ which contact the flanges C⁶ C⁷. This structure will be clear from Figure 5.

I may provide any suitable oil circulating means for delivering oil from the oil housing to the bearings. I indicate for example a gear P upon the shaft D which gear meshes with and drives a pinion P¹. The shaft P², associated with the pinion, may drive any suitable pump mounted for example in the pump housing P³ and not herein shown in detail. P⁴ indicates an oil delivery pipe extending from the pump housing, along which the pump is adapted to direct a flow of oil. P⁵ indicates an oil pipe extending from the oil reservoir to the pump, through which oil is drawn for delivery along the pipe P⁴. P⁴ communicates with an oil duct P⁶ which extends to the packing gland P⁷ and communicates with an axial passage P⁸ in the shaft D. Outlets P⁹ for the said duct P⁶ are adapted to deliver oil to the bearing surface of the eccentric D¹. The oil may escape along the bushing D⁹ and may drip back into the oil reservoir. The bearings D⁴ which journal the shaft D are lubricated by the same oil stream or oil delivery through the outlets P²⁰ communicating with the oil duct P⁸. P¹⁰ indicates an oil delivery pipe extending to the axial or longitudinal passage P¹² in the shaft B⁴, as illustrated in Figures 3 and 4. P¹³ indicates oil outlet ducts through the bearing surface of said shaft. They extend for example to the milled-out portion P¹⁴ in the shaft B⁴. The oil may escape along the bushing B⁵ into the chambers or pockets P²¹ which may be closed as by the packing members P²⁹. Communicating with the chambers P²¹ are the drain ducts P²² through which the oil may flow into the passage P²³. P²⁴ indicates a return oil duct whereby the oil from the passage P²³ is delivered into a chamber P²⁵ having an outlet P²⁶ at a point adjacent the roller D¹³ which is thereby lubricated. The oil drips back into the reservoir. The baffle O⁶ serves to prevent the drip or delivery of oil to the wiping member O⁵. P¹⁶ indicates oil

return ducts from the oil collecting housings or members P¹⁷, in one of which the pump drive is positioned as shown in Figures 1 and 5. Thereby all the oil delivered to the bearings D⁴ is returned to the oil reservoir. P¹⁸ indicates an oil inlet pipe, having the cap P¹⁹, whereby any desired quantity of oil may be delivered to the oil reservoir.

Referring to Figure 3, P²⁷ indicates any suitable relief valve whereby excess pressure in the oil ducts P⁴, P⁶ and P¹⁰ may be eliminated, the expelled oil is returned into the oil chamber through the duct P²⁸. P³⁰ indicates a sight feed oil gauge.

It will be observed that the oscillation or movement of the lower jaw structures progressively increases and diminishes the volume of air within the oil reservoir, owing to the fact that the cavity of the oil reservoir opens to the lower face of the plate C¹. As the jaw rises there is a tendency to suck air into the oil housing and as the jaw falls there is a tendency to expel air. In order to prevent admission of dust by such air flow I provide an air inlet shown for example in Figure 2 as follows. Q indicates the main air inlet passage closed by a perforated plate Q¹. The perforations Q² are masked by a flexible diaphragm Q³, which permits movement of air downwardly through the apertures, but resists movement of air upwardly through the apertures, being flattened against the plate Q¹ by any upwardly exerted air pressure. Q⁴ indicates a passage in communication with the top of the plate Q¹. It is surrounded by a generally rectangular housing Q⁵ with a perforated bottom Q⁶ and any suitable dust retaining filling Q⁷, for example of fiber. Q⁸ indicates a closed cover which, however, may be removed, as by loosening of the wing nuts Q⁹ mounted on the pivoted eye-bolts Q¹⁰. The result is the admission of dust-free air into the oil housing, through the aperture Q, associated with means for preventing retrograde movement of air upwardly through the aperture Q. It will be understood from this structure that as the jaw plate C¹ rises, air is drawn through the aperture Q. As the jaw falls air is forced downwardly around the packings O⁴ O⁵ O⁷, blowing away the dust, or preventing the inward movement of dust or dust filled air into the oil housing.

It will be realized that although I have described and shown a practical and operative device, nevertheless many changes may be made in the size, shape, number and disposition of parts without departing from the spirit of my invention. I therefore wish my description and drawings to be taken as in a broad sense illustrative and diagrammatic rather than as limiting me to my specific showing. In particular it will be understood that I do not wish to be limited, except so far as I limit myself in my claims, to any

particular shape or profile or angle of crushing jaw or plate, as I may vary them considerably without destroying the characteristic action of the crusher.

5 The use and operation of my invention are as follows:

I employ a jaw crusher having preferably an inclined, lower jaw, and an upper jaw overhanging or overlying a substantial portion 10 of the area of the lower jaw. In the particular form of my device herein shown the lower jaw C^1 is pivoted adjacent or above the upper edge of its effective crushing area, and is oscillated or rotated, through a rather substantial arc, about its pivot, in such fashion 15 that the travel or throw of the crushing plate G increases progressively from top to bottom. The driving connection is made from the lower portion of the crushing jaw, whereby the eccentric D^1 by its rotation oscillates or pivots the jaw C^1 , giving the plate G its characteristic crushing movement. The upper or overhanging jaw M , with the crushing plate M^1 is normally fixed upon the frame 20 of the crusher. However, I provide a yielding connection between the upper jaw structure and the frame, whereby it may give in response to the passage of uncrushable material through the crushing machine.

30 I claim:

1. In a jaw crusher, a normally fixed jaw and a moving jaw opposed thereto, and actuating means for said moving jaw and a housing to the rear of said moving jaw, adapted 35 to surround said actuating means, a portion of the moving jaw forming a closure for said housing, a lubricant within said housing and means for directing said lubricant to said actuating means.

40 2. In a jaw crusher, a normally fixed jaw and a moving jaw opposed thereto, a housing to the rear of said moving jaw, eccentric actuating means for said jaw, positioned within said housing, a body of lubricant 45 within said housing, a pivotal mounting adjacent the upper portion of said jaw, means for delivering lubricant from said housing to said pivotal mounting, and for returning said lubricant thence to the housing.

50 3. In a jaw crusher, a normally fixed jaw and a moving jaw opposed thereto, and actuating means for said moving jaw including an eccentric member and means for rotating it, a housing positioned to the rear of said moving jaw and surrounding said eccentric, said jaw being adapted to form a closure for said housing, a lubricant within said housing, pumping means associated with said eccentric, a bearing upon which said moving jaw 55 is rotatably mounted, and means for conducting oil from said pump to said bearing.

60 4. In a jaw crusher, a normally fixed jaw and a moving jaw opposed thereto, and actuating means for said moving jaw including an eccentric member and means for rotating it, a

housing positioned to the rear of said moving jaw and surrounding said eccentric, said jaw being adapted to form a closure for said housing, a lubricant within said housing, pumping means associated with said eccentric, a bearing upon which said moving jaw is rotatably mounted, and means for conducting oil from said pump to said bearing, and means for returning oil from said bearing to said housing.

Signed at Hollywood, county of Los Angeles and State of California, this 16th day of July 1930.

EDGAR B. SYMONS.
